UNITED STATES PATENT OFFICE.

HUBERT P. RYNER, OF OMAHA, NEBRASKA, ASSIGNOR TO HOESCHEN MANUFACTURING COMPANY, A CORPORATION OF NEBRASKA.

SIGNAL-ACTUATING MECHANISM.

1,165,540.

Specification of Letters Patent. Patented Dec. 28, 1915.

Application filed March 11, 1915. Serial No. 13,797.

To all whom it may concern:

Be it known that I, HUBERT P. RYNER, a citizen of the United States, residing at Omaha, in the county of Douglas and State 5 of Nebraska, have invented certain new and useful Improvements in Signal-Actuating Mechanism, of which the following is a specification.

My invention relates to mechanism for 10 actuating railway-crossing signals, and particularly to signal-actuating mechanism employing a mechanical energy-storing device, such as a spring-motor, operatively connected with the signal mechanism, and having 15 suitable means for controlling the operation of the energy-storing device.

It is the object of my invention to provide, in combination with mechanism of the 20 described character, electrically-actuated means for winding the spring-motor, or supplying the primary energy to a like energy-storing device, said electrically-actuated means being controlled by the operation of 25 the signal mechanism so that the winding of the motor is automatically proportioned to the duration of operation of the signals.

Constructions embodying my invention are illustrated in the accompanying drawings, in which—

30 Figure 1 is a front view of the motor and its controlling and winding mechanism, Fig. 2 is a side view of the same, Fig. 3 is a side view, partly in section, showing a characteristic arrangement of the signal mechanism, 35 Fig. 4 is a detail sectional view on the plane of the line $x-x$ of Fig. 2, Fig. 5 is a detail side view of a part of the controlling mechanism, Fig. 6 is a detail front view of parts 40 of the controlling mechanism, and Fig. 7 is a diagram of the electrical connections of the apparatus.

In carrying out my invention I preferably employ a motor and controlling mechanism therefor of the general character shown in 45 the patent application of Henry A. Hoeschen, filed Dec. 13, 1911, Serial No. 665,575, and signaling mechanism of the general character shown in the patent application of Henry A. Hoeschen, filed March 7, 1913, 50 Serial No. 752,762. I have herein illustrated and will describe such portions of

said motor-controlling and signaling mechanism as are pertinent to my invention, but it will be understood that such mechanism, in so far as it embodies the subject-matter 55 of the applications above set forth, is the invention of the said Henry A. Hoeschen and is disclaimed by me except as a part of the combined structures herein set forth, or as an element of the combinations herein 60 claimed.

In the arrangement of the signal mechanism shown in Fig. 3 there is erected, at or near the railway crossing to be protected, a suitable supporting column 1 which carries 65 a casing 2 inclosing the actuating mechanism. From the upper part of the casing a tubular column-portion 3 extends up and supports the signal devices. The latter comprise a swingable bell 4 inclosed within 70 a cage 5 under a canopy 6, and a swinging arm 7 disposed outside the cage, as shown. Both the bell and arm 7 are actuated by a rod 8 which extends up through the column-portion 3 and to which a reciprocating 75 movement is imparted by the means herein-after described.

Within the casing 2 is a suitable frame 9 in which is journaled the horizontal motor-shaft 10. On said shaft is carried the escape-wheel 11, and above said wheel the verge-beam 12 is pivotally mounted on a horizontal shaft 13. The verge-beam carries pallets 14 and 15 adapted to be engaged by the teeth of the escape-wheel to cause an 80 oscillating movement of the beam about its pivotal axis. The rod 8 is connected with one end of the verge-beam and its reciprocating movement is received from the beam. On the side of the escape-wheel is carried 85 one or more small rollers 16 adapted to engage a stop-block 17 which is pivotally connected with the frame by means of a shaft 18 journaled in the front frame-plate. On the front end of the shaft 18 is secured the 90 stop-arm 19 which extends upwardly therefrom, the upper end of the arm being adapted to engage a latch 20 pivoted on the frame as shown in Fig. 1. The weight of the stop-block tends to move the arm to a position at 95 which it will be engaged and held by the latch. When the arm is so held, the stop-

block is thereby retained in such a position that the rollers 16 cannot pass it. When the latch is disengaged from the stop-arm the pressure of the roller engaging the stop-block swings the same upwardly, the block and arm passing momentarily to the positions shown by dotted lines in Fig. 6, so that the rollers can pass beneath the block, and the escape-wheel revolve in the direction indicated. After the roller passes out of engagement with the stop-block the latter will move back toward its normal or initial position, and the stop-arm, if not prevented from so doing, will reengage the latch so that when the block is again engaged by one of the rollers the movement of the escape-wheel will be stopped. For lifting the latch 20 to release the stop-arm and permit operation of the signals, one or more electro-magnets 21 are provided, each having a movable armature 22 of which a portion extends beneath the head of a pin 23 on the latch. Said electromagnets 21 are connected in a circuit or circuits controlled by movement of trains along the railway track toward the crossing at which the signal mechanism is placed, such circuits usually being arranged so that one of the magnets will be energized whenever a train approaches to within a predetermined distance from the crossing.

For holding the stop-arm temporarily in release position, a drop-lever 24 is pivoted on the frame as shown. When the stop-arm returns toward normal position, after being moved to release position, a shoulder on the lower edge of the lever 24 is engaged by a pin 25 on the rearward side of the arm, and thus prevents return movement of the arm far enough to enable its engagement by the latch 20. The operation of the signals will thus continue until the drop-lever is raised to disengage the shoulder from the pin 25, and thus permit return of the stop-arm to normal position and engagement with the latch 20. The drop-lever may be raised to free the stop-arm therefrom, by energization of an electromagnet 26, whose armature 27 is connected with the lever as shown. The drop-lever may also be raised by means of a timing device which is adapted to actuate the lever after the signals have been in operation for a predetermined time. A toothed rack-bar 28 is held slidably in a slightly inclined position by suitable guides on the front side of the frame, the lower portion of the rack-bar extending adjacent to the front end of the motor-shaft 10. On said end of the shaft is a small disk carrying a pin 29 which is adapted to engage the teeth on the bar, and intermittently lift the bar as the shaft revolves. A pawl 30, pivoted on the frame as shown, is adapted to engage the teeth on the rack-bar to retain the same in the successive positions to which it may be

raised by the rotation of the motor-shaft. The pawl 30 is engageable by a tail-portion 31 on the stop-arm, and is thereby held out of engagement with the rack-bar when the stop-arm is in normal position, but when the stop-arm is in release position the pawl falls into engagement with the rack-bar and prevents downward movement thereof. The upper end of the rack-bar extends toward the end of the drop-lever, and after the rack-bar has been moved upward far enough to engage it the drop-lever is thereby lifted to free the stop-arm. The stop-arm then moves to normal position, being there engaged and held by the latch 20, the tail-portion 31 disengages the pawl 30 from the rack-bar so that the same can fall back to its lower position, and all the parts are thus restored to normal position simultaneously with the stopping of the motor-shaft.

For actuating the motor-shaft 10 there is provided a spiral spring 32 of which the inner end is connected directly with the shaft, as shown in Fig. 4. The spring is inclosed within a drum or casing 33 which is secured on one side of a ratchet-wheel 34, said wheel being revolubly mounted on the shaft, and the outer end of the spring being connected with a pin 35 on the side of the wheel within the inclosing drum. A pawl 36 mounted on the shaft 13 engages the ratchet-wheel to prevent retrograde movement thereof. Adjoining the rearward side of the ratchet-wheel an arm 37 is pivoted on the motor-shaft, said arm extending out beyond the periphery of the wheel and having pivoted on the outer end a pawl 38 which engages the toothed edge of the wheel. Said outer end of the pawl-arm is connected by a rod 39 with the end of an armature-lever 40 which is fulcrumed on a shaft 41 extending horizontally between the frame-plates. The lever 40 carries an armature 42 which is positioned beneath the poles of an electromagnet 43 so as to be pulled upwardly when said electromagnet is energized. On one end of the verge-beam 12 a contact-arm 44 is secured thereto, being insulated therefrom but movable as a part thereof. Arcuate contact-plates 45 and 46 are mounted on projecting lugs 47 on the frame, said contact-plates being insulated from the frame and being positioned adjacent to the path of movement of the outer end of the contact-arm 44 so as to be alternately engaged thereby during the oscillating movements of the verge-beam. Between the adjacent ends of the contact-plates 45 and 46 there is a space or gap, and, when the verge-beam is in the normal position assumed when rotation of the escape-wheel is prevented by the stop-block, the end of the contact-arm 44 is opposite said gap and out of contact with both the plates 45 and 46. The contact-plates are connected by wires 48 with one side of a suitable battery

or electrical generator 51; from the other side of said generator a connection 49 is extended to the electromagnet 43, and from the electromagnet a connection 50 is extended to the contact-arm 44, as represented in Fig. 7.

From Fig. 7 it will be seen that the circuit through the electromagnet 43 is normally open, so that said magnet is not energized, but that immediately upon commencement of operation of the signal mechanism the circuit will be closed by the engagement of the arm 44 with one of the contact-plates 45 and 46. The magnet, being thus energized, raises the armature-lever 40 and pawl-arm 37, thereby advancing the ratchet-wheel 34 and increasing the tension of the motor-spring 32. As the oscillatory movement of the verge-beam is continued the circuit is broken each time the contact-arm passes the gap between the adjacent ends of the contact-plates, the armature-lever and pawl-arm being thereby permitted to drop down to their normal or initial position, but being immediately pulled up again as the circuit is reestablished. The winding of the motor-spring 32 is thus automatically proportioned to the duration of operation of the oscillating signal mechanism.

In connection with the foregoing mechanism there is provided, at the railway crossing near which the signal mechanism is placed, a suitable track instrument A (indicated in Fig. 3) adapted to operate a switch or circuit-closing device when a train passes over the track at the crossing. The electrical connections of the track instrument are indicated in Fig. 7. The circuit-closing device 52 is connected in series with the battery or generator 51 and the electromagnet 26, by means of wires 53 and 54 which, in practice, are extended from the track-instrument to the signal mechanism through a pipe or conduit B, as shown in Fig. 3. The circuit through the magnet 26 is normally open at the device 52, but is closed during the passage of a train over the track-instrument, so that the magnet is then energized and raises the drop-lever 24, thereby stopping the operation of the signal mechanism which will have been previously started into operation by the approach of the train to the crossing.

Now, having described my invention, what I claim and desire to secure by Letters Patent is:

1. In a signaling mechanism, a mechanical energy-storing device, signal-actuating elements connected therewith to be driven thereby, means for controlling said elements, electrically actuated means for supplying energy to said energy-storing device, a circuit controlling said electrically-actuated means, and means connected with the signal-actuating elements and controlling said cir-

cuit to automatically proportion the energy-supply of the storing device to the rate of operation of the signals.

2. In a signaling mechanism, a motor-spring, signal-actuating devices connected therewith to be driven therefrom, means for controlling movement of said devices, electrically-actuated winding-means for the motor-spring, and means connected with the signal-actuating devices and controlling said winding-means to cause operation thereof simultaneously with operation of the signals.

3. In a signaling mechanism, a motor-spring, an oscillating signal-actuating element movable thereby, means for controlling movement of the motor, electrical winding-means for the motor-springs, a winding-circuit, and controlling means connected with the oscillating signal-actuating element and adapted to close the winding-circuit only during periods of movement of said element.

4. In a signaling mechanism, a spring-motor, a signal-actuating element movable thereby, means for stopping the motor to retain said element at a fixed normal position, electrically-driven winding-means for the spring-motor, and a circuit-controlling device for said winding means, said circuit-controlling device being connected with the signal-actuating element and opening the circuit when said element is in normal position.

5. In a signaling mechanism, the combination with a motor-spring, an escape-wheel driven thereby, a verge-beam actuated by said escape-wheel, a stop for said wheel adapted to hold the same at a position for retaining the verge-beam in a normal fixed position, and means for controlling the stop, of oscillatory winding-means for the motor-spring, an electromagnet for actuating said winding-means, a winding-circuit for said electromagnet, and a circuit-controller in said circuit and connected with the verge-beam so as to be closed when the beam moves from normal position.

6. In a signal mechanism, a motor-spring, means for holding the same under tension, reciprocating means for increasing the tension of the spring, an electromagnet for actuating said reciprocating means, an electrical circuit formed through said electromagnet, a circuit-controller for said circuit, and signal-actuating means driven by the motor-spring and connected with the circuit-controller to operate the same synchronously with the signals.

7. In a signal mechanism a motor-spring, winding means therefor, electrical actuating means for the winding means, a circuit controlling said actuating means, an element connected in said circuit and having a normal fixed position at which the circuit is opened thereby, a signal-actuating member

connected with said element for moving the same from normal position to close the circuit simultaneously with movement of the signal, and means operatively connecting the motor-spring and signal-actuating member whereby the latter may be actuated by the spring.

In testimony whereof I have hereunto subscribed my name in the presence of two witnesses.

H. P. RYNER.
